DI(HYDROCARBON SUBSTITUTED)POLYAMINE
FUEL DETERGENTS

Enver Mehmedbasich, El Cerrito, Calif., assignor to
Chevron Research Company, San Francisco, Calif.
No Drawing. Continuation of abandoned application Ser.
No. 750,765, Aug. 7, 1968. This application Dec. 7,
1970, Ser. No. 95,962

Int. Cl. C10I 1/22

U.S. CL. 44—58

6 Claims

ABSTRACT OF THE DISCLOSURE

Bis(oil solubilizing hydrocarbon) substituted alkylene polyamines having from 2 to 5 amine nitrogen atoms, wherein the oil solubilizing hydrocarbon groups are of from 25 to 50 carbon atoms, are effective fuel detergents having good water tolerance.

This application is a streamlined continuation of Ser. No. 750,765, filed Aug. 7, 1968, now abandoned.

BACKGROUND OF THE INVENTION

Field of the invention

Fuel detergents have been used for a long time to maintain clean carburetors in gasoline internal combustion engines. Further efforts have been employed to obtain detergents which not only clean the carburetor but also clean the intake ports and valves. These detergents are referred to as having extended detergent action (EDA).

By cleaning the ports and valves, the engine operates more efficiently. Thus, the useful life of the engine is extended before major repairs are required. The fuel is used more efficiently, reducing the amount of unburned fuel which is exhausted. More efficient use of fuel reduces the extent of pollution of the air.

Co-pending application Ser. No. 538,571, filed Mar. 30, 1966, now abandoned, discloses a wide variety of hydrocarbon substituted alkylene polyamines for use as fuel detergents. However, some improvement in water tolerance was found to be desirable.

Description of the prior art

U.S. Pat. No. 3,275,554, patented Sept. 7, 1966, discloses a wide variety of hydrocarbon substituted alkylene polyamines for use as detergents in lubricating oils.

SUMMARY OF THE INVENTION

Alkylene polyamines having from 2 to 5 amine nitrogen atoms and at least 70 percent of the alkylene polyamines being disubstituted with hydrocarbon solubilizing groups of from 25 to 50 carbon atoms are used as fuel detergents showing good water tolerance.

DESCRIPTION OF THE PREFERRED EMBODIMENTS

The compositions of this invention will have at least 70 weight percent of a composition of the formula:

wherein U is alkylene of from 2 to 6 carbon atoms, preferably of from 2 to 3 carbon atoms, there being at least 2 carbon atoms between the nitrogen atoms; n is an integer of from 1 to 4, preferably of from 2 to 3; and R is a hydrocarbon fuel solubilizing group of from 25 to 50 carbon atoms, more usually of from 30 to 45 carbon atoms and preferably polypropenyl and polyisobutyl.

R, for the most part, will be an aliphatic group, preferably branched, having not more than about 2 sites of ali-

phatic unsaturation, e.g., ethylenic. Usually, R will be a branched chain aliphatic hydrocarbon group having at least one branch of about 1 to 4 carbon atoms per four atoms along the longest chain. Preferably, the branch is methyl.

Depending on the method of preparation, small amounts of chlorine may be present on the hydrocarbon group R. Usually, residual chlorine will be less than about 2 weight percent.

10 The preferred alkylene polyamines are polyethylene polyamines, such as triethylene tetramine and tetraethylene pentamine. Equivalent to the alkylene polyamine are compositions which frequently are formed concurrently in the preparation of the alkylene polyamines, such as N-aminoethyl piperazine.

15 The compositions of this invention may be prepared in a variety of ways which insure that at least 70 weight percent of the composition is disubstituted. The other materials present will ordinarily be mono-substituted alkylene polyamines and tri- or higher substituted alkylene polyamines.

20 To insure that the predominant product is the disubstituted compound, the compositions may be conveniently prepared stepwise. That is, the alkylene polyamine is reacted with alkenyl chloride in the presence of excess of

25 alkylene polyamine to prepare the mono-substituted product. The excess amine is then removed and an additional stoichiometric equivalent of alkenyl halide is added to provide the disubstituted product. Of course, the same or different alkenyl groups may be used, as long as they are within the indicated carbon range.

30 Usually, the amine reactants will not be individual compounds but mixtures of compounds having an average composition. Ordinarily, these compositions have a predominant compound present with minor amounts of other materials to provide the average composition indicated. When polymers are used as the hydrocarbon substituent, the average molecular weight is indicated and usually at least 70 weight percent of the polymer will be within plus or minus 20 weight percent of the average composition indicated.

35 The preparation of the compositions is carried out in a manner analogous to that described in co-pending application Ser. No. 538,571. The aliphatic halide, preferably alkenyl chloride, is combined with the desired alkylene polyamine, either neat or in the presence of an alkanol of from 3 to 6 carbon atoms, aromatic hydrocarbon or mixtures thereof.

40 Elevated temperatures are ordinarily used in the range of about 50° to 150° C., more usually from about 75° to 125° C. The time for the reaction will generally vary from 2 to 12 hrs.

45 The detergent will generally be employed in a hydrocarbon base liquid fuel. The detergent additive may be formulated as a concentrate, using a suitable hydrocarbon or alcohol solvent boiling in the range of about 150° to 400° F. Preferably, an aromatic hydrocarbon solvent is used, such as benzene, toluene, xylene or higher boiling aromatics or aromatic thinners. Aliphatic alcohols of about 3 to 8 carbon atoms, such as isopropanol, isobutylcarbinol, n-butanol and the like, in combination with hydrocarbon solvents are also suitable for use with the detergent additive. In the concentrate, the amount of the additives will be ordinarily at least 10 percent by weight and generally not exceed 70 percent by weight.

55 The amount of the detergent used in the fuel will generally be from about 100 to 1,000 p.p.m.

60 In gasoline fuels, other fuel additives may also be included such as antiknock agents, e.g., tetramethyl lead or tetraethyl lead. Also included may be lead scavengers such as aryl halides, e.g., dichlorobenzene or alkyl halides, e.g., ethylene dibromide.

A nonvolatile lubricating mineral oil, e.g., petroleum spray oil, particularly a refined naphthenic lubricating oil having a viscosity at 100° F. of 1,000 to 2,000 SUS, is a suitable additive for the gasoline compositions used with the detergents of this invention and its use is preferred. These oils are believed to act as a carrier for the detergent and assist in removing and preventing deposits. They are employed in amounts from about 0.05 to 0.5 percent by volume based on the final gasoline composition.

EXAMPLES

The following examples are offered by way of illustration and not by way of limitation.

5. A fuel composition concentrate having from 10 to 70 weight percent of a composition of the formula:

wherein U is alkylene of from 2 to 6 carbon atoms, n is an integer of from 1 to 4 and R is a hydrocarbon fuel solubilizing group of from 25 to 50 carbon atoms, the remainder of said detergent composition being mono- and tri- or higher-substituted alkylene polyamines, and wherein in said detergent composition is prepared by reacting an alkenyl chloride with an excess of alkylene polyamine and the reaction product is then reacted with about a stoichiometric equivalent amount of alkenyl chloride; and a solvent boiling in the range of about 150-400° F. compatible with liquid hydrocarbon fuel.

6. A composition according to claim 5, wherein in said detergent composition, R is polypropenyl or polyisobut enyl and U is alkylene of from 2 to 3 carbon atoms.

UNITED STATES PATENT OFFICE
CERTIFICATE OF CORRECTION

Patent No. 3,746,520 Dated July 17, 1973

Inventor(s) ENVER MEHMEDBASICH

It is certified that error appears in the above-identified patent and that said Letters Patent are hereby corrected as shown below:

Col. 4, line 13, "ASTM D-1049" should read --ASTM D 1094--.

Claim 1, "[HN(UN)_nHR₂H_{n-1}]" should read --(HN(UN)_nH)R₂H_{n-1}--.

Signed and sealed this 5th day of March 1974.

(SEAL)
